US00D868669S

(12) **United States Design Patent** (10) **Patent No.:** **US D868,669 S**
(45) **Date of Patent:** **** Dec. 3, 2019**

(54) **JOYSTICK**

(71) Applicant: **ISRAEL AEROSPACE INDUSTRIES LTD.**, Lod (IL)

(72) Inventors: **Eyal Kruk**, Petah Tiqwa (IL); **Omer Frank**, Tel Aviv (IL)

(73) Assignee: **ISRAEL AEROSPACE INDUSTRIES LTD.**, Lod (IL)

(**) Term: **15 Years**

(21) Appl. No.: **29/691,363**

(22) Filed: **May 15, 2019**

Related U.S. Application Data

(62) Division of application No. 29/612,243, filed on Jul. 31, 2017.

CLAIM

The ornamental design for a joystick, as shown and described.

DESCRIPTION

FIG. 1 is a front perspective view of a new design for a joystick;

FIG. 2 is a top perspective view thereof;

FIG. 3 is another top perspective view thereof;

FIG. 4 is a right perspective view thereof;

FIG. 5 is top view thereof;

FIG. 6 is a bottom view thereof;

FIG. 7 is a right view thereof;

FIG. 8 is a left view thereof;

FIG. 9 is a front view thereof; and,

FIG. 10 is a rear view thereof.

1 Claim, 10 Drawing Sheets
